UNITED STATES PATENT OFFICE.

ARTHUR E. TEAL, OF WALKER TOWNSHIP, KENT COUNTY, MICHIGAN.

PHONOGRAPH.

1,336,492.

Specification of Letters Patent. Patented Apr. 13, 1920.

Application filed March 24, 1919. Serial No. 284,864.

To all whom it may concern:

Be it known that I, ARTHUR E. TEAL, a citizen of the United States, residing in Walker township, in the county of Kent and State of Michigan, have invented new and useful Improvements in Phonographs, of which the following is a specification.

The present invention relates to phonographs; and an object thereof is to provide

a phonograph improved in various features of construction; a further object is to provide a phonograph having improved resonant qualities; a further object is to provide a phonograph having an outer wall sufficiently strong and rigid but nevertheless vibratile under the action of sound waves; a further object is to provide in a phonograph an improved sound amplifier; a further object is to provide in such an amplifier a plurality of branches so disposed interrelatively that the sound waves issuing therefrom intersect and blend; a further object is to provide a phonograph wherein the vibratile outer wall of the phonograph forms a wall of the amplifier; a further object is to provide an amplifier having a middle and side branches; a further object is to provide an improved valve for governing the volume of sound issuing from the amplifier; a further object is to provide an improved counterbalancing device for the hinged cover of the cabinet.

These and any other objects hereinafter appearing are attained by, and the invention finds preferable embodiment in, the structure hereinafter described and illustrated by the accompanying drawings, in which:

Figure 1 is a central vertical section of a phonograph;

Fig. 2 is a sectional view of the same taken on a horizontal plane corresponding to line A—A of Fig. 1;

Fig. 3 is a central section of the same taken on a vertical plane corresponding to line B—B of Fig. 1; and

Fig. 4 is a section of the same taken on vertical planes corresponding to line C—C of Fig. 3.

In the embodiment of the invention chosen for illustration by the drawings and for detailed description in the body of this specification, the phonograph has a cabinet or casing circular (or substantially so) in horizontal section. In an annular groove 1 in the cabinet's bottom 2 and in a like

groove 3 in the partition 4 intermediate the bottom and the top of the cabinet, the edges of the lower section 5 of the curved side wall of the cabinet are securely seated, 60 while the lower edge of the arcuate upper section 6 of the side wall is similarly seated in the annular groove 7 in the upper side of said partition, the ends of this arcuate member being securely connected to a hinge-supporting member 8, such connection of one end of the arcuate member being indicated in Fig. 1.

The record support or turntable 9 above the partition 4 is rotated by suitable means (not shown) in the chamber 10 below the partition. The swingable tone arm 11 carries suitable sound reproducing means (not shown) and communicates through a sound passage 12 in the partition with the horn 75 or sound amplifier which comprises a vertical member 13 and branches leading therefrom through orifices 14, 15, 16 respectively. The middle branch 17 has side walls 18, 19, and the outer or side branches 20, 21 have 80 inner walls 22, 23 respectively (see Fig. 2), their outer walls being parts of the curved outer wall of the cabinet itself. The mutually adjacent walls 19, 22 and 18, 23 of the side branches and of the middle branch are 85 in non-parallel relation and are respectively spaced apart by the spaces 24, 25. The lower section 5 of the cabinet's outer wall has an opening 26 therethrough, which may be filled by a preferably removable grille 90 27, through which opening the sound waves pass from the phonograph. It will be seen (particularly in Fig. 2) that the side branches of the amplifier curve toward each other toward their mouths, so that the 95 sound waves issuing from all the branches intersect and blend at the mouths of the branches. This provision has the effect of modifying and softening the tone which leaves the instrument and strikes the ear. 100

The upper walls 28 of the side branches curve upwardly (as particularly shown in Figs. 1 and 4) so that the sound passages therein gradually widen toward their mouths in a vertical direction and also in 105 a horizontal direction as seen in Fig. 2. It will be seen that the walls of the amplifier's branches, as well as the walls 29, 30 containing the motor, form chambers within the casing. These walls are preferably vibratile under the influence of sound waves, particularly the walls 18, 19, 22, 23, 28 and 110

also the lower section 5 of the cabinet's side wall, and are tightly secured in place, as by gluing, so as to be resonant and form essentially sound boards for augmenting and mellowing the sound. The curved walls are preferably formed of bent wood. It will be seen that the cabinet's outer wall being thus formed, will be vibratile and nevertheless sufficiently strong and rigid for the outer wall of the instrument.

A valve 31 swingable on its pivot 32 and having a lever arm 33 for swinging it is located in the main or vertical portion of the amplifier. This valve is cut away at 34 adjacent the opening 14 into the middle branch 17 so as to provide a passage in the valve through which sound waves will pass in any position of the valve and particularly into the middle branch 17. The valve may be swung to increase or diminish the volume of sound passing to all the branches by means of a handle 35 extending through and slideable in a slot 36 in the partition 4 and having a link 37 connected to the valve's lever arm.

A cover 38 hinged at 39 to the hinge-supporting member 8 at the rear of the cabinet may be opened to expose the record support, etc. A counterbalancing device for the opening and closing cover is provided comprising the rod or plunger 40 vertically movable and connected at its lower end to the lever arm 41 fulcrumed at 42, which arm is spring-pressed at 43 in the direction of the cover's opening movement. The upper end of this plunger is pivoted at 44 to a link 45 pivoted at 46 to the cover inwardly from the hinge 39.

It will be seen that in the closed position of the cover this spring is under increased tension and that as the cover opens the tension is lessened. When the cover is moved to fully opened position, (shown in dotted lines in Fig. 1) the pivot 46 passes between the hinge and the longitudinal axis of the plunger and the cover is thus held against falling shut; and when the cover is swung to closed position, said pivot 46 passes to the opposite side of the plunger's said axis. As shown, a pair of these plungers, etc., are preferably provided.

The valve 31 is preferably of wood and made by gluing two disks 47, 48 together with the spindle 49 between them. It will be seen that the manually operated means for turning the valve is located inside the cabinet.

A sound deflector 50 is located at the bottom of the main portion 13 of the sound amplifier, and has surfaces 51, 52 curving from a middle ridge 53 toward the side branches respectively of the amplifier, and also a surface 54 curving toward the middle branch. When the valve is turned on its spindle 49 to open position, the edge of the

valve approximately fits the apex of the ridge as seen in Fig. 1.

The invention being intended to be pointed out in the claims, is not to be limited to or by details of construction shown or described.

1. claim:

1. In a phonograph; sound reproducing means; a tone arm; a sound amplifier leading from the tone arm, and having branches so interrelatively disposed that the sound waves issuing from one branch intersect and blend inside the amplifier with those issuing from the other branch, the mutually adjacent sides of the branches being in non-parallel relation and their inner surfaces being convex.

2. In a phonograph; sound reproducing means; a tone arm; a sound amplifier leading from the tone arm, and having branches so interrelatively disposed that the sound waves issuing from one branch intersect and blend inside the amplifier with those issuing from the other branch, the mutually adjacent walls of the branches being spaced apart and their inner surfaces being convex.

3. In a phonograph; sound reproducing means; a tone arm; a sound amplifier leading from the tone arm, and having a middle branch and side branches curving toward each other toward their mouths, the branches being so interrelatively disposed that the sound waves issuing therefrom intersect and blend.

4. In a phonograph; sound reproducing means; a tone arm; a sound passage leading from the tone arm; a vibratile curved outer wall of the phonograph constituting a wall of the sound passage and extending beyond the inner wall of the amplifier.

5. In a phonograph; sound reproducing means; a casing containing the same; a record support within the casing; partitions within the casing and so disposed as to form a chamber beneath the record support adapted to contain means for moving said support, and to form also a sound amplifier having a middle branch and side branches curving toward each other toward their mouths.

6. In a phonograph; sound reproducing means; a casing containing the same and being substantially circular in horizontal section; a record support within the casing; partitions within the casing and so disposed as to form a chamber beneath the record support adapted to contain means for moving said support, and to form also a sound amplifier having a middle branch and side branches curving toward each other toward their mouths.

7. In a phonograph; sound reproducing means; a casing containing the same and being substantially circular in horizontal section; a record support within the casing;

105

110

115

- partitions within the casing and so disposed as to form a chamber beneath the record support adapted to contain means for moving said support, and to form also a sound amplifier having a middle branch beneath the chamber and side branches curving upwardly above the top of the middle branch and toward each other toward their mouths.
8. In a phonograph; sound reproducing means; a casing containing the same and being substantially circular in horizontal section; a record support within the casing; partitions within the casing and so disposed as to form a chamber beneath the record support adapted to contain means for moving said support, and to form also a sound amplifier having a middle branch and side branches spaced from the middle branch by non-parallel walls and curving toward each other toward their mouths.
9. In a phonograph; sound reproducing means; a tone arm; a sound amplifier leading from the tone arm and having a main portion and a middle branch and side branches; a valve in the main portion having an opening adjacent one branch and being movable to govern the volume of sound passing to all the branches.
10. In a phonograph; sound reproducing means; a tone arm; a horizontal partition carrying the tone arm and having a sound passage therethrough, a sound amplifier below the partition and leading from the tone arm and said passage and comprising a vertical main portion and a middle sound discharging branch and side sound discharging branches; a valve in the main portion to govern the volume of sound; means extending through the partition for moving the valve.
11. In a phonograph; sound reproducing means; a tone arm; a sound amplifier comprising a main portion and a middle branch and side branches; a sound deflector in the main portion having surfaces curving from a middle ridge toward the side branches respectively and a surface curving toward the middle branch; a valve in the main portion turnable on an axis diametrical to the main portion and whose edge in the open position of the valve approximately fits the apex of said ridge.

In testimony whereof I have hereunto set my hand at Grand Rapids, Michigan, this 21st day of March, 1919.

ARTHUR E. TEAL.
